STATIC ELIMINATION IN MANOMETERS

Charles F. Wallace, Westfield, N. J., assignor to
 Wallace & Tiernan Products, Inc., Belleville,
 N. J., a corporation of New Jersey

Application March 12, 1945, Serial No. 582,340

2 Claims. (Cl. 73—401)

1

My present invention relates to static elimination in manometers and more particularly to manometers such, for example, as a mercury barometer, wherein means are provided for preventing the effect upon the height of the mercury column of static electricity which causes some inaccuracies in the readings.

In working with manometers, particularly mercury barometers, it has been found that the presence of static electricity inside the transparent tube containing a column of liquid, the height of which is indicative of a pressure or other condition to be measured, causes relatively small, but appreciable, errors in the height of the liquid column. For example, in a mercury barometer, this error may be in the order of magnitude of .005 inch of mercury. Where the utmost accuracy is of importance, it is necessary that means be provided for eliminating this error. The provision of such means is a primary object of the present invention.

The presence of static electricity has been noted in the following way. If a small piece of very thin aluminum foil is cemented on the upper edge only to the side of a tube and is bent so that its bottom edge is approximately $\frac{1}{8}$ " from the tube such as a glass tube containing a mercury column and the mercury run up or down several times past the place at which the aluminum foil is secured, it will be found that when the mercury rises upwardly past the aluminum foil, the uncemented part of the latter will remain outwardly away from the tube; and when the mercury is moved down past this foil, it will move toward the tube and stay close to the glass. When, however, a tube used for a liquid column to measure pressure is treated as hereinafter more particularly set forth and in accordance with the present invention, this effect is not present. Further, upon comparison between an untreated manometer and one constructed or prepared in accordance with the present invention, it is found that the untreated manometer usually shows a higher reading if it has been used recently, in the order of magnitude of .005 inch of mercury, than that of the treated manometer. The fact that the mercury itself is electrically conducting apparently does not serve to bleed such static electricity away from the surface of the tube in which it is enclosed, as the phenomenon has been particularly noticed as aforesaid in connection with mercury barometers. It is assumed, but not herein relied upon that in the case of mercury manometers at least, the mercury has a charge of one sign (either positive or negative) while the glass has a charge of the

2

opposite sign, i. e. either negative or positive (respectively). It has been suggested that a theory tending to explain this phenomenon is that the mercury does not wet the tube and hence does not have such contact therewith as can bleed an electrical charge from the inside walls of the tube. However, the present invention is not predicated upon any particular theory; and this is only suggested by way of possible explanation.

A further and more specific object of the present invention is to provide an inside coating on a manometer tube of the above described character, which will be in close contact with the tube and will be per se electrically conducting, while being sufficiently transparent or translucent, so as to permit a visual reading of a height of the liquid column in the tube and so that any static electricity which may accumulate inside a tube by reason of the liquid therein being moved up and down or for any other reason, may be bled off to a suitable ground so that it will not interfere with the liquid column attaining a level accurately indicative of the magnitude of a condition to be indicated thereby.

Other and more detailed objects of the present invention will become apparent from the following specification and appended claims, when taken in connection with the accompanying drawings, in which:

30 Figure 1 is a fore-shortened view, partly in elevation and partly in central vertical section, showing a portion of a mercury barometer wherein in the tube is coated interiorly in accordance with the present invention; and

35 Fig. 2 is a detail view in horizontal section on the line 2—2 of Fig. 1.

I have chosen to illustrate my invention as applied to a mercury barometer, although I contemplate that it is equally applicable to any and all types of manometers and also may be applicable to manometers using liquids other than mercury.

The drawings illustrate a mercury barometer including a container 1, which may be constructed in the usual manner to contain a pool of mercury and which may have an opening to the atmosphere through a top portion 2 thereof or may be connected in a manner (not shown) to a vessel in which there is a gaseous pressure which it is desired to indicate. There is provided a tube 3 in the usual manner, which preferably extends down into a pool of mercury inside the container 1, but does not extend completely to the bottom thereof, this tube preferably being of transparent or translucent material such as glass. The indicating liquid, in this case mercury, is shown at

45 50 55

4 up to a height or level indicated at 5 in the tube. Thus, if the level of the mercury in the container 1 is maintained at a given point in any suitable manner known to the art, the height of the column of mercury 4, that is the level or top surface 5, may be read in connection with an appropriate gauge or scale in any desired and/or known manner. The construction thus far described may be considered as the standard equipment of the prior art.

As above set forth, I have found that the presence of static electricity which tends to collect on the inside surface of the tube 3 causes the error in the height of the mercury column, which tends to cause it to read high and by an amount which has been found to be in the order of magnitude of .005 inch.

My present invention provides means for bleeding off this static electricity, so that it will not interfere with or affect the height of the column. For this purpose I preferably provide on the inside surface of the tube 3 a coating of some electrically conductive material, which preferably also is sufficiently transparent or translucent so that the height of the liquid, that is the level 5, may be visually read or otherwise ascertained. While I contemplate that various types of coatings might be adequate for this purpose, including sprayed metal, the type I have found most advantageous for practical use is a thin film deposited from an aqueous colloidal solution of graphite, such as that known commercially as "Aquadag." This coating is shown diagrammatically in the accompanying drawings at 6. It will be understood that while the layer 6 as shown in the drawings is of substantial thickness, this is for illustrative purposes only and is not to be taken as an accurate illustration indicative of the actual dimensions of the thickness of the coating which is in practice very thin, so that it will not seriously interfere with the transparency or translucency of the coated tube and thus interfere with a visual reading of the height of the top surface level 5 of the liquid column. Preferably the entire interior surface of the tube is coated, although I contemplate that if only that portion extending for a substantial distance above and below the probable height of the liquid column 5, many, if not all, the desired results of this

invention would still be attained. In view of the fact that most liquids used in manometers are per se to some extent electrically conducting, it has been found that there will be a sufficient contact if the tube is coated for a substantial length below the surface of the liquid 5 to effect a bleeding off and consequent grounding of the static electricity from the layer or coating 6 to the fluid itself.

10 While I have shown and specifically described herein but one embodiment of the present invention and have pointed out in connection with this description the essential characteristics thereof, it will be understood that various modifications 15 may be made therein within the above teachings and as will be apparent to those skilled in the art therefrom. I do not wish to be limited, therefore, except by the scope of the appended claims, which are to be construed validly as broadly as the state of the prior art permits.

20 What I claim is:

25 1. A manometer, comprising a non-metallic and non-electric conducting tube containing a liquid, the level of the surface of which in said tube is indicative of the magnitude of a condition, and an electrically conducting coating inside said tube and in contact with said tube and with the liquid therein for bleeding off static electricity on the inside of said tube, so as to prevent any effect 30 of such static electricity upon the level of the surface of the liquid in said tube.

35 2. A manometer in accordance with claim 1, wherein said tube is a transparent glass tube, said coating is a substantially transparent layer of graphite, and said liquid is mercury.
